& TORLEY COMPANY, OF PITTSBURGH, PENNSYLVANIA, A CORPORATION OF
PENNSYLVANIA.

DRAFT GEAR.

Application filed May 21, 1923. Serial No. 640,494.

My invention relates to draft gear for railway cars and particularly to the type wherein the cushioning unit involves the use of friction elements. The principal object of the invention is to provide a yoke device of easily manufactured form suitable for cooperating with a cushioning unit of the friction type and capable of being operatively connected to a car coupler by either a vertical or a horizontal key.

A primary feature of the invention, generally stated, consists in constructing a draft gear with a yoke device formed with a casing to which are integrally united a pair of forwardly extending slotted arms which, adjacent their forward ends, are integrally united by oppositely disposed side walls terminating in advance of said casing, the said arms being provided with a pair of vertically aligned key slots adapted to receive a coupler connecting key, said side walls being formed with horizontally aligned key slots open at their rear ends and adapted to receive a coupler connecting key, a car coupler having a stem whose rear end is received in the hollow hood constituted by the said arms and side walls, a key extending through said coupler and through one or the other pair of said slots, and a follower movably mounted between and projecting laterally beyond the said arms in advance of the casing.

A further feature of the invention involves a yoke device comprising a casing closed at its rear end, a pair of vertically aligned slotted arms integrally united to and extending forwardly from the casing, and side walls integrally uniting said arms in advance of said casing, the said arms at points to the rear of the slots therein being of less width than the casing, the said side walls being formed with a pair of key slots open at their rear ends, said arms and said side walls forming a hollow hood for receiving the stem of a car coupler, and either of the pairs of key slots being adapted to receive a key for movably connecting a car coupler to the yoke device.

Other features of the invention involving advantageous details of construction and particular relations of parts will herein-after appear.

In the drawings illustrating the inven-

tion, the scope whereof is pointed out in the claims:

Figure 1 is a plan view of a draft gear embodying the invention, stationary parts of the car with which it is associated being shown in dotted lines.

Figure 2 is a side elevation of the construction shown in Fig. 1.

Figure 3 is a transverse section on the line 3—3, Fig. 1, the coupler connecting key being in elevation.

In the drawings 1 indicates the stem of a car coupler and 2 is the yoke device. The coupler 1 is shown as provided adjacent its rear end with a slot 3 for receiving a vertically extending key 4 by which the coupler and draft yoke are operatively connected. As will hereinafter appear, the yoke device is not only adapted to be connected to a car coupler provided with a slot for receiving a vertically extending connecting key, but also is provided with means enabling it to be attached to a coupler having a horizontal slot for the reception of a correspondingly disposed key.

The yoke device has a hollow casing 5 which preferably is closed at its rear end. This casing is made of any desired shape and size suitable for receiving and cooperating with the springs and friction elements of the cushioning unit housed therein, the cushioning unit being diagrammatically indicated in the drawings by the diagonal dotted lines 6 in the conventional manner. In buffering the rear end of the casing 4 abuts against draft lugs 7 or other suitable stops rigidly attached to the center sills or draft sills 8 of the car in a well known manner.

Integrally united to the casing 5 and extending forwardly therefrom is a pair of vertically spaced arms 9 rigidly united in advance of the casing by side walls 10 formed as an integral part of the yoke device. The rear ends of the side walls 10 terminate in advance of the casing at a distance preferably amply sufficient to permit the easy introduction into the casing of the springs and friction elements of the cushioning unit. The side walls 10, together with the vertically aligned arms 9, form a hollow hood for receiving the rear end of the coupler stem 1, the said side walls preferably being spaced apart a distance somewhat

2
greater than the width of the neighboring portion of the coupler stem and diverging forwardly so as to provide for lateral swinging movements of the coupler. The arms 9 are furnished with vertically alined key slots 11 for receiving the key 4 when it is disposed in vertical position, the said slots being of a length sufficient to permit said key to travel rearwardly therein during a 10 buffing movement of the coupler and being flared or widened from their forward ends rearwardly, as indicated at 12, to permit the angular turning movement of the key when the coupler executes a lateral swinging movement. When, as shown in the drawings, a 15 downwardly removable vertical key 4 is employed for connecting the coupler to the yoke device, the lower arm 9 is preferably provided upon opposite sides of the adjacent key slot 11 with downwardly extending shouldered lugs 13 for sustaining a slide or plate 14 which passes under the key 4 and thus maintains it in assembled position. The plate 14 may be held in place by a cotter 15 passing through the reduced end of the plate and overlapping the rear ends of the lugs 13.

To the rear of their slots 11 the vertically spaced arms 9 are somewhat reduced in 30 width so as to permit the follower 16 movably mounted between the arms 9 to project laterally beyond said arms in advance of the forward end of the casing 5. The ends of the follower 16 are adapted during a 35 draft movement of the coupler to bear against draft lugs 17 riveted or otherwise rigidly secured to the car sills 8.

The side walls 10 are also provided with 40 key slots adapted to receive a horizontally extending key for operativley connecting the coupler to the draft yoke. These horizontally alined slots 18 are in open communication at their rear ends with the space in which the follower 16 operates, thus enabling 45 a coupler connecting key extending through said slots to travel rearwardly with the coupler in a buffing operation, while at the same time enabling the side walls 10 of the yoke device to be spaced well in advance of the casing 5. By this means the permissible 50 length of the casing may be increased without unduly lengthening the yoke device. The draft lugs or follower stops 17 and the adjacent car sills 8 are suitably slotted, as indicated at 19, to permit a horizontal coupler connecting key to travel with the coupler 55 during draft and buffing movements.

The arms 9 as well as the side walls 10 may be thickened toward their forward ends 60 to provide ample bearing area for the forward edge of the coupler key, and said arms may advantageously be provided on their inner faces with transversely extending shoulders 20 adapted to limit forward 65 movement of the follower 16 when the cou-

pler 1 is disconnected from the yoke device 2.

My invention provides a strong and simple draft yoke device formed as an integral casting and enables the friction casing portion thereof to extend for a comparatively 70 great proportion of the entire length of the device.

I claim:—

1. A draft gear involving a yoke device provided with a casing and having a pair of vertically alined arms integrally united to and extending forwardly from said casing and also having oppositely disposed side walls spaced in advance of said casing and integrally uniting said arms, said arms being provided with key slots and at points to the rear of said slots being of less width than said casing, said side walls having horizontally alined key slots and terminating in advance of the forward end of the casing 85 so as to afford space permitting the introduction of cushioning means into said casing, a car coupler having a stem interposed between said arms and said side walls, said coupler being adapted to move longitudinally with respect to said yoke, a key extending through said coupler and entering one pair of said slots, and a follower movably mounted between and projecting laterally beyond said arms in interposed relation to 95 said side walls and casing.

2. A draft gear involving a yoke device provided with a casing closed at its rear end and having a pair of vertically alined arms integrally united to and extending forwardly from said casing and also having oppositely disposed side walls spaced in advance of said casing and integrally uniting said arms, said arms being provided with key slots extending in the direction of 100 length of said yoke device, said side walls terminating in advance of the forward end of the casing so as to afford space permitting the introduction of cushioning means into said casing and being formed with 105 key slots which are open at their rear ends, a car coupler having a stem interposed between said arms and side walls and movable longitudinally with respect to said yoke device, a key extending through said coupler 110 and cooperating with one pair of said slots, and a follower movably mounted between and projecting laterally beyond said arms in advance of said casing.

3. A yoke device for railway draft gear comprising a casing, a pair of vertically alined arms integrally united to and extending forwardly from said casing, and side walls spaced in advance of said casing and integrally uniting said arms, said side walls and arms constituting a hollow hood adapted to receive the stem of a car coupler, said arms being provided with a pair of alined key slots, said side walls terminating in advance of the forward end of the casing so 120 125 130

as to afford space permitting the introduction of cushioning means into said casing and being formed with a pair of aligned key slots which are open at their rear ends, and 5 either of said pairs of slots being adapted to receive a key for connecting the car coupler to the yoke device.

4. A yoke device for railway draft gear comprising a casing closed at its rear end 10 and adapted to permit the introduction of cushioning means at its forward end only, a pair of vertically aligned arms integrally united to and extending forwardly from said casing, said arms being provided with a pair

of key slots and at points rearwardly of said slots being of less width than said casing, and side walls integrally uniting said arms and spaced in advance of said casing, said side walls being formed with a pair of key slots which are open at their rear ends, said 20 arms and said walls constituting a hollow hood adapted to receive the stem of a car coupler, and either of said pairs of slots being adapted to receive a key for connecting a car coupler to the yoke device. 25

In testimony whereof I affix my signature.

ENOCH GEORGE, JR.
